UNITED STATES PATENT OFFICE

WARREN T. HUNT, OF TOLEDO, OHIO, ASSIGNOR TO THE WILLYS OVERLAND CO., OF
TOLEDO, OHIO, A CORPORATION OF OHIO

SHEET METAL LEVER

Application filed January 18, 1930. Serial No. 421,797.

This invention relates to lever and more particularly to levers which are formed from sheet metal and usually known as stampings.

One of the objects of the invention is to provide a lever that is rigid and cheap to manufacture.

Another object of the invention is to provide a sheet metal lever which may be easily clamped upon an operating shaft.

Other objects will appear from the description to follow, in connection with which I have illustrated two embodiments of the invention in the accompanying drawing, in which.

Figure I is a side view of the improved lever shown in position on a portion of an operating shaft.

Fig. II is a rear view of the lever shown in Figure I.

Fig. III is a side view of a modified form of a lever embodying the invention.

Fig. IV is a rear view of the lever shown in Fig. III.

Fig. V is a sectional view taken along the line V—V of Fig. III.

Referring to the form shown in Figures I and II, 10 is a U-shaped lever formed from a single piece of sheet metal, the sides 12 and 14 being bent to normally lie substantially parallel to each other, and with the web portion 16 connecting the sides at the bottom of the U. Web portion 16 may, if desired, extend along one side of the lever 10 for substantially its entire length, but I prefer to have it relatively short as compared with the periphery of the lever in order to eliminate difficulties in manufacturing and permit the upper ends of the lever to be unsupported.

The sides 12 and 14 are provided with aligned holes 22 and 24, which are slightly larger in diameter than the operating rod 26.

Adjacent web 16 are provided aligned holes 18 and 20 for the reception of a clevis pin 28 to which is pivotally attached the operating rod 30. The upper ends of sides 12 and 14 are provided with a bolt 32 having a nut 34 which is used to force the sides 12 and 14 toward each other and out of their normal parallel position. A key 36 interlocking with both lever 10 and shaft 26 is also used to pre-

vent relative rotative movement between the two members.

In assembling lever 10 to the shaft 26, the lever is slipped over the end of the shaft which may be easily done, because of the aligned holes 22 and 24 being slightly greater than the shaft 26, and pushed to its desired position as shown in Fig. II. Bolt 32 is then tightened, which causes sides 12 and 14 to be forced out of parallel and to be convergent toward their upper ends, the bottom being held in spaced relation by the web 16. The distortion of the sides 12 and 14 causes the holes 22 and 24 to be thrown out of alignment and their inner edges to closely grip the shaft 26 and lock the lever in position. A slight wedge-shaped clearance will occur at the upper side of the lever as indicated by 38 in Fig. II but which is immaterial as the gripping of the inner edges has been found sufficient for locking the lever in position.

Referring to the form shown in Figs. III, IV and V, sides 40 and 42 are connected by a web 44 and stop lugs 46 and 48 are formed intermediate the web 44 and shaft 26 for preventing the inward movement of the lower portion of sides 40 and 42, which form the lever 50. Lugs 46 and 48 are preferably formed by inwardly striking portions on the sides 40 and 42 and are of such length as to allow the lower portions of sides 40 and 42 to be parallel when the lugs are in an abutting position.

The lever 50 is assembled to the shaft 26 in the same manner as lever 10 and when the bolt 32 is tightened the upper ends of sides 40 and 42 will be forced out of parallel and clamp lever 50 upon the shaft 26. In this form of the invention the side portions between the lugs and the web will be parallel in the clamped position and all the distortions will occur in the unsupported portions above the lugs.

While I have shown and described somewhat in detail certain embodiments of my invention, it is understood that this showing and description are illustrative only and that I do not regard my invention as limited to the form shown and described except where-

in I have included such limitations within the terms of the following claims.

I claim:

1. A lever formed of sheet metal blank having aligned shaft receiving openings and sides normally parallel, a web connecting said sides, portions of the sides adjacent the shaft receiving holes being unsupported; means for forcing the sides out of parallelism adjacent the openings, portions of the side walls of the lever being struck up laterally, said struck up portions adapted for engagement to limit the movement of the sides; and a second pair of substantially aligned openings adjacent the web portion adapted to receive connecting means.
2. In a lever formed from a sheet metal blank having sides normally parallel throughout their length, an integral web connecting the sides; a pair of aligned holes adjacent the web for receiving a pivotal member; a pair of aligned holes for receiving a shaft;

rectangular key ways in the parallel arms of said lever adjacent and intersecting the shaft receiving holes, said keyways adapted to receive a member carried by the shaft, said sides being supported adjacent the shaft receiving holes; and means for forcing out of parallelism the portions of the lever sides which contain the shaft receiving holes.

3. A lever formed from a sheet metal blank having U-shape with normally parallel sides throughout their length, said sides having elements in circular openings for receiving a shaft; means including a bolt arranged substantially parallel with the axis of said shaft for forcing the sides out of parallelism to retain the lever to said shaft, a portion of the side walls of the lever being struck up laterally and adapted for engagement to limit the movement of the sides.

In testimony whereof, I affix my signature.

WARREN T. HUNT.
